UNITED STATES PATENT OFFICE.

ROBERT B. JONES, OF MONTPELIER, VERMONT, ASSIGNOR TO JONES BROTHERS COMPANY, OF BOSTON, MASSACHUSETTS, A CORPORATION OF MAINE.

GRINDING MACHINE AND METHOD.

1,290,224.

Specification of Letters Patent.

Patented Jan. 7, 1919.

Application filed August 3, 1918. Serial No. 248,123.

To all whom it may concern:

Be it known that I, ROBERT B. JONES, citizen of the United States of America, and resident of Montpelier, in the county of Washington and State of Vermont, have invented new and useful Improvements in Grinding Machines and Methods, of which the following is a specification.

This invention relates to grinding apparatus and more particularly to apparatus for finishing a corrugated stone mortar and coöperating stone roll for use in pulverizing materials such as chocolate.

The mortar is concave on its upper side, the concave surface being substantially cylindrical and having corrugations extending in the direction of the cylindrical curvature. The roll has corrugations around the periphery thereof in planes perpendicular to the axis of the roll, the corrugations on the roll being adapted to register with the corrugations in the block. In grinding materials such as chocolate the roller is rolled back and forth over the block with its corrugations intermeshing with the corrugations in the block.

The principal object of the present invention is to grind pairs of mortars and rolls of the character referred to so that the roll and mortar of each pair will accurately fit together and to provide apparatus for accomplishing this end quickly and easily. Another object is to produce the desired finish on the coöperating surfaces of the roll and mortar. Still other objects will be evident from the following detailed description of one embodiment of my invention.

Figure 1 is a side elevation of the grinding machine;

Fig. 2 is an end elevation of the machine viewed from the right of Fig. 1, parts being omitted;

Fig. 3 is a section on line 3—3 of Fig. 1; and

Fig. 4 is a perspective view of the block to be ground.

The stone block B illustrated in Fig. 4 is first provided with a concave cylindrical upper surface S and corrugations C are then cut in the upper surface in the direction of the curvature of the surface. These operations may be performed in any suitable manner, the corrugations C preferably being roughed out by hand. As shown in Fig. 4 the corrugations do not extend to the edges

of the block but terminate somewhat short of the ends so that in using the blocks the chocolate will be confined to the corrugated surface. Likewise the corrugations in the roll R are first roughed out by hand or in other suitable manner. After the corrugations are roughed out on the roll and mortar respectively the two parts are ground together, as will be described hereinafter, until the corrugated surfaces are smooth and until the corrugations intermesh accurately.

The machine forming the subject matter of the present invention comprises, in general, a horizontal supporting frame 1, an oscillatory frame 2 depending therefrom, the frame 2 being journaled on the horizontal frame 1 by means of bearings 3, a rotatable shaft 5 journaled in the lower end of frame 2, a longitudinally adjustable link 6 for oscillating the frame 2, a motor 7 for driving the parts and transmission mechanism hereinafter described, for connecting the motor with the operative parts of the machine. The roll R is fixedly mounted on shaft 5 which extends through an axial opening in the roll. The block B may be supported in any suitable manner but when composed of granite or other stone it is relatively heavy and is therefore preferably supported on a carriage 8 mounted on the track 9 so that the block can be readily moved into and out of position beneath the roll R.

The depending frame 2 comprises two bars 11 and 12 connecting at their upper ends to bearings 13 and 14 which are rotatably supported on the shaft 15, the shaft 15 being journaled in the bearings 3. At the lower end the arms 11 and 12 connect with bearings 16 and 17 which rotatably support the shaft 5 upon which the roll R is fixedly mounted. The two arms 11 and 12 are joined together near their lower ends by two cross bars 18 and 19, the link 6 being connected to the center of the bar 19. Pulleys 20 and 21 are fastened to the outer ends of shaft 5 and pulleys 22 and 23 are fastened to the outer ends of the shaft 15 and belts 24 and 25 connect together the pulleys of the two sets. At the center of the shaft 15 is mounted a pulley 26 which serves as the driving pulley for shaft 15.

Power is transmitted to the pulley 26 from the motor 7 through the medium of two pulleys 27 and 28 mounted on a counter shaft 29, the pulley 27 being connected to the mo-

tor by means of a belt 30 and the pulley 28 being connected to the pulley 26 by means of a belt 31. Power is transmitted to the link 6 from the counter shaft 29 through the medium of belt 32, pulley 33, shaft 34, pinion 35, gear wheel 36, shaft 37, and wheel 38, the wheel 38 having a crank arm 39 pivotally connected to the end of the link 6.

The supporting frame 1 for the oscillatory frame 2 carrying the roll R is preferably comprised as follows: The frame 1 is supported at one end on the uprights 40 and 41 by means of a shaft 42 extending through slots 43 and 44 in the uprights 40 and 41, the horizontal frame 1 having plates 45 and 46 bolted to its opposite sides and the plates 45 and 46 having openings therein to receive the shaft 42; and the opposite end of the frame 1 is supported on the superstructure 47 by means of a screw 48 which is threaded through the horizontal member 49 of the superstructure and which is provided at its upper end with a collar 50 having an annular groove therein to receive the plate 51 fastened to the lower side of the cross beam 52 extending between the longitudinal beams 1-1.

The operation of the machine is as follows: The roll R and block B having been roughed out as previously described are brought into the position shown in Figs. 1 and 2, with the corrugations on roll R intermeshing with the corrugations on block B. Upon starting the motor 7 the roll R is rotated through the medium of belt 30, pulley 27, shaft 29, pulley 28, belt 31, pulley 26, shaft 15, pulleys 22 and 23, belts 24 and 25, pulleys 20 and 21 and shaft 5; and the frame 2 is oscillated to and fro by the link 6 as the wheel 38 is rotated. As the roll R is simultaneously rotated and oscillated to and fro over the surface of the block B the corrugations on the roll and block are gradually smoothed off and rendered uniform and even, iron sand and emery powder being successively applied to the surfaces of the roll and block during the grinding process. As the rough corrugations in the roll and block are gradually smoothed down it is necessary gradually to lower the roll and this may be accomplished either manually or automatically.

The manual method of feeding the roll downwardly consists in allowing the shaft 42 to rest in the bottom of the grooves 43 and 44 at all times and gradually lowering the right hand end of the horizontal support 1 by means of the hand wheel 53 on screw 48. The automatic method of feeding the roll downwardly during the grinding operation consists in pulling the right-hand end of support 1 downwardly by means of screw 48, with the roll R resting on the block B, until the shaft 42 is lifted from the bottom of the slots 43 so that the entire

weight of the roll R, depending frame 2, horizontal support 1, etc., urges the roll against the block. With the parts thus adjusted the shaft 42 gradually settles in the slots 43 and 44 as the corrugations are ground down and by properly adjusting the wheel 53 the cutting operation can be automatically stopped when the shaft 42 reaches the bottom of the slots 43 and 44.

A salient advantage of the support comprising shaft 42 resting in slots 43 and 44 is that should the roll R strike an abnormal projection on the block B the shaft 42 can move upwardly in slots 43 and 44 and thus permit the roll to ride over the protuberance, thus avoiding injury to the roll or other parts of the machine. Moreover the slot connection permits the roll to be lifted while the block is being positioned thereunder.

When feeding the roll R downwardly by the automatic method above described it will be observed that the frame 1 and the parts carried thereby are supported wholly on the block B and that the frame 1 is fixedly attached to the superstructure only at the center of its right-hand end by means of screw 48. Any tendency for the frame 1 to tip laterally about the end of the screw 48 is counteracted by the corrugations in roll R extending into the grooves in block B. Moreover owing to the fact that the frame 1 is otherwise free to tip laterally about the supporting screw 48 the corrugations on the grinding roll R automatically adapt themselves to the grooves in the block B.

While I have described the present invention for use in grinding a stone block and a stone roller, it is to be understood that it may be used to grind or otherwise cut other materials and that while the roll and the block have been described as mutually grinding each other the parts could be so constructed that one part would grind or otherwise cut the other part without being materially affected itself.

What I claim is:

1. In a grinding machine of the character described, the combination of a horizontal member, an arm depending from said member, a bearing for pivotally connecting said arm to said member, means to oscillate said arm to and fro in said bearing, a grinding roll rotatably mounted on the lower end of said arm, means to rotate said roll while the arm is swinging to and fro, and a vertical guideway for said member, the member being vertically movable in said guideway so that said roll may be raised and lowered into position on the stock and so that the roll is held against the stock by gravity during the grinding operation.

2. In a grinding machine of the character described, the combination of a horizontal member, an arm depending from said

member, a bearing for pivotally connecting said arm to said member, means to oscillate said arm to and fro in said bearing, a grinding roll rotatably mounted on the lower end 5 of said arm, means to rotate said roll while the arm is swinging to and fro, means for supporting said member on one side of said bearing, and a vertical guideway for said member on the other side of said bearing, 10 whereby when the grinding roll is positioned upon suitably prepared stock the roll is held against the stock and automatically advanced into the stock by gravity.

3. The method of producing a grinding 15 roll and mortar with corrugations which accurately intermesh with each other comprising first roughing out complemental

corrugations in the roll and mortar and then rolling the roll to and fro over the mortar with the corrugations in the roll and mortar 20 intermeshing until the corrugations are worn accurately to interfit.

4. The method of producing a grinding roll and mortar with corrugations which accurately intermesh with each other comprising first roughing out complemental corrugations in the roll and mortar, moving the roll to and fro over the mortar with the corrugations in the roll and mortar intermeshing, and rotating the roll as it is moved 25 back and forth over the mortar.

Signed by me at Montpelier, Vermont,
this 30th day of July, 1918.

ROBERT B. JONES.
